UNITED STATES PATENT OFFICE.

JAMES W. MCNEIL, OF NEWARK, NEW JERSEY.

PRINTING-PRESS.

1,285,759.

Specification of Letters Patent. Patented Nov. 26, 1918.

Application filed February 4, 1915. Serial No. 5,991.

To all whom it may concern:

Be it known that I, JAMES W. MCNEIL, a subject of the King of England, and a resident of Newark, in the county of Essex and State of New Jersey, have invented certain new and useful Improvements in Printing-Presses, of which the following is a specification.

The objects of the invention are to provide a printing press in which a flat stationary form is employed over which paper carrying cylinders roll or travel; to support the form upon a member around which the paper carrying cylinders can continuously revolve or travel; to provide suitable mechanism for revolving said paper carrying cylinders around the form supporting member; to enable the inking rolls to be also carried by said revolving means; to secure speed in a flat form press without great strain; to guide the cylinders across the form with an even pressure; to provide means for releasing said pressure, and means for removing the cylinders from contact with the form whereby the printing does not take place; to positively rotate said cylinders independent of their contact with the form; to provide a drive for positively rotating the ink rolls; to support the ink rolls as they pass over the form to relieve the pressure thereon; to provide such supporting means which are adjustable and adapted to compensate for the shrinkage and wear of the rolls; to provide an extensive inking surface for the ink rolls; to provide a rotary member for applying fresh ink to said ink rolls; to provide improved means for operating the paper gripping means; to secure simplicity of construction and operation, and to obtain other advantages and results as may be brought out in the following description.

Referring to the accompanying drawings, in which like numerals of reference indicate the same parts throughout the several views,

45 Figure 1 is a side elevation of a press embodying my invention;

Fig. 2 is a vertical sectional view taken just inside of the frame as upon line A—A of Fig. 6;

50 Fig. 3 is a similar section, taken through the center of the press, as upon line B—B of Fig. 6;

Fig. 4 is a detail sectional view of the

driving means for the supplying roll of the ink fountain;

55 Fig. 5 is a detail sectional view on line C—C of Fig. 3;

Fig. 6 is a transverse sectional view as on line D—D of Fig. 3;

Fig. 7 is a detail sectional view showing 60 the operating means for the paper gripping mechanism, and

Fig. 8 is a side elevation of a portion of the rotating disk, showing the adjustable supporting means for the ink rolls.

65 In the specific embodiment of the invention illustrated in said drawings, the reference numerals 1, 1 indicate parallel spaced side pieces or frames joined by suitable tie bars 2. Extending between said side pieces 70 is a stationary shaft 3 having keys 4 or other suitable means for preventing its rotation with respect to said side pieces, and mounted intermediate of the side pieces upon said shaft is a bed or form-supporting member 5 75 secured non-rotatably upon the shaft, as by keys 6, so as to be stationary. At one side of the form-supporting member, the same provides a flat surface recessed as at 7 for supporting the form, and, preferably, from 80 said flat surface a continuous surface 8, substantially cylindrical, extends around said member, from one end to the other of the flat surface. A chase 9 may be secured within the recess 7 to support the form 10 there- 85 in, and ink rolls 11, 11 are provided which will rotate across the form and around the substantially cylindrical surface 8 to recross the form always in the same direction. Said surface 8 is utilized for the inking surface 90 for said rolls, and the rolls will therefore be freshly inked each time before passing over the form. Following the ink rolls around the form member is a paper carrying cylinder 12, suitably held out of contact with the 95 inking surface 8, adapted to support and carry a sheet of paper across the form to obtain an imprint therefrom upon the paper. Obviously as many of these paper carrying cylinders may be employed as desired,

100 and for purposes of illustration I have shown two situated diametrically upon opposite sides of the form-supporting member. Furthermore, the ink rolls may be in sets of as many rolls as necessary to properly ink 105 the form, and preferably one set in advance

of each of the paper carrying cylinders. As shown, there are two rolls in each set, and two sets diametrically opposite each other and arranged half way between the cylinders 12.

In order to support and revolve the paper carrying cylinders and ink rolls around the form-supporting member 5, disks 13, 13 are provided at both ends of said member, adapted to rotate upon the shaft 3, and upon the outer sides of these disks 13, 13 and connected thereto are gear wheels 14, 14 also loose on said shaft and meshing with idler gear wheels 15, 15 which in turn mesh with driving gears 16, 16 upon a driving shaft 17, which extends between the said side pieces 1.

1. Upon one end of this shaft is shown a suitable hand wheel 18 and at the other end is shown a driving pulley 19 adapted to be driven by a belt to rotate said disks continuously through the train of gearing above described.

Since the bed or form-supporting member is not a true cylinder, but is flattened at one side to receive the form, which is also flat, it is necessary that as the ink rolls and paper carrying cylinders revolve around the form-supporting member, they be permitted to move radially of said member toward and away from the shaft 3 as they advance across said form. Referring first to the construction illustrated for permitting this radial movement for the ink rolls, it may be noted that any suitable and well-known means may be employed. For purposes of illustration carriers 20 are provided each comprising a rod 21 slidable longitudinally and extending substantially radially of the disk, said rod having a hook or other means 22 at its outer end for releasably engaging the ink roll. The rod is resiliently drawn inward by a suitable spring 23 and given sufficient range of movement longitudinally to allow the roll to not only pass around the inking surface 8 but to engage the form when passing thereover.

For permitting the necessary radial movement of the paper carrying cylinders with respect to the form member, each of the disks 13 is slotted for each of the cylinders radially of itself, as at 24, and provides at the longitudinal or radial edges of each slot ways or guides slidably carrying a floating journal 25 for the paper carrying cylinder.

Between the inner ends of the slots 24 and the journal boxes are springs 26 tending to slide the paper carrying cylinders to their outer positions. Means are provided for actuating the paper carrying cylinders and their journals inwardly of the disks 13 and maintain the cylinders in proper operative relation to the form. The means shown comprises opposite compression rails 27, 27 attached to the side pieces or frames 1, 1 in planes perpendicular to the cylinders and

at their ends. Rollers 28 on the cylinders engage and are guided by said compression rails as they pass thereunder, and said rails are positioned and arranged to thus guide the cylinders across the form. Furthermore, 70 the portions of the rails engaged by the rollers while the cylinder is passing over the form, are parallel to the plane of the form so that an even pressure is exerted at all parts of the form. It may here be noted 75 that the cylinder will engage the form upon only a line or very narrow strip longitudinally of itself at any one moment while being rolled thereover, so that a maximum printing pressure is secured with minimum 80 pressure against the rails on the frame.

It is often desirable to allow a paper carrying cylinder to pass over the form but sufficiently removed therefrom to not receive an impression, and to effect this I support 85 the compression rails each at their opposite ends upon similar eccentrics 29 rotation of which will move the said rails toward and away from the bed. Said eccentrics are mounted non-rotatably upon rock shafts 30 90 carried in brackets 31 extending from the side pieces or frames, and the rails are prevented from displacement off the eccentrics by engagement with the ends of said brackets on one side and by a cap or head 32 upon the 95 other side larger than the eccentric and fast with respect thereto. The outer ends of the rock shafts carry levers 33 for rocking said shafts, and for so rocking them simultaneously a link 34 extends between each pair 100 of levers for each rail, and a treadle rod 35 connects one of the levers of one rail to a crank 36 on the end of a treadle shaft 37 extending between the side pieces or frames. On the opposite end of this treadle shaft is 105 secured a treadle 38 to which is directly connected a treadle rod 39 from one of the eccentric operating levers on that side of the press. By depressing the treadle, all of the eccentrics are turned at once and thus raise 110 the compression rails. Preferably the rotation of the eccentrics is limited as by stops 40 on the levers engaging suitable pins 41 on the frame, and furthermore a suitable spring 42 is provided to hold the treadle 115 normally raised and the compression rails in lowered position.

A positive drive is preferably provided to rotate the cylinders as they pass over the form, independent of contact of said cylinders with the form, and to this end I provide at the opposite ends of the cylinders between the same and the driving disks 13, 13 a pair of similar gear wheels 43 fast with respect to said cylinders. Preferably the 120 diameters of the pitch circles of the gear wheels are the same as the diameter of the rolling surface of the cylinder. At opposite ends of the bed or form-supporting member are racks 44, 44 following the contour of 125

said member and in mesh with the above described gear wheels 43 of the cylinder. Obviously, as the cylinders are caused to revolve around the form supporting member 5 they rotate upon their own axes, and with the pitch lines of the racks in the plane of the form, each cylinder rolls without slipping with respect to said form. Furthermore, it is preferable for the racks to be continuous around the form-supporting member 10 and the parts properly proportioned so that the same portions of the cylinder surface engage the form each time it crosses the same.

It is preferable to relieve the racks and 15 gear wheels of any pressure so as to allow the same to operate accurately and with the least possible wear and noise. For this purpose tracks 45 are provided one at each end of the form-supporting member 5 continuous 20 forming in configuration to the contour of said member and positioned between the end of the member 5 and the adjacent rack 44. The cylinder has a roller 46 overlying each of these tracks, positioned upon its supporting axle between the gear wheel and the 25 end of the cylinder. This roller has been shown for purposes of illustration as a distinct member from the rollers 28 for engagement with the compression rails. The 30 construction shown, however, is such as to allow an idle roll 76 to be rotatably secured to the disks at the inner end of radial movement of the cylinder against which the compression roller 28 will engage at its inner 35 position while the cylinder is crossing the form.

The ink rolls preferably are provided at their opposite ends with pinions 47 in mesh with the racks 44 on the form-supporting member so as to positively rotate 40 the ink rolls.

Preferably adjustable idle rollers 48 are carried by the disks 13 for limiting inward movement of the ink rolls so as to assist in 45 obtaining an even distribution of the ink as the rolls pass over the form. The construction shown comprises a bar 49 arranged transverse to the several rods of the roll carriers and carrying the idle rollers 48, 50 one for each ink roll. Said bar is secured to the outer side of the disks by screws 50, which pass through lateral slots 51 in the bar whereby said bar may be moved laterally of itself toward and away from the ink 55 rolls. Bolts 52 in the plane of the bars on the opposite sides thereof from the ink rollers are supported in suitable lugs 53 on the disks and are adapted to engage the bar to prevent displacement thereof radially inward 60 of the disks. Suitable rollers 77 on the ends of the ink rolls will engage and ride upon the idler rollers 48 as the ink rolls pass over the form.

It may be here noted that the ink rolls 65 are allowed to revolve around the form-

supporting member in contact therewith so as to properly work the ink and be themselves properly coated with ink, but by virtue of the track 45, the cylinders are revolved around the form-supporting member 70 without engaging the inked surface.

In order to supply fresh ink to the inking surface, a suitable ink fountain 54 is provided, the same being here shown as positioned upon the lower tie bar 2 at the front of the press. The usual supply roll 55 extends longitudinally of this fountain 54, in direct contact with the ink. Ductor rolls 56 are provided to transfer the ink from the supply roll 55 to the inking rolls 11, and preferably a continuous rotary motion is given said ductor rolls instead of a reciprocating or oscillating motion. To this end an axle 57 is rotatably mounted at the front of the frames above the ink fountain and has secured fast upon itself a pair of transverse plates 58 between which at their outer ends are mounted the ductor rolls in floating bearings held by springs 59 normally at their radially outward position. It will be understood that as the ductor rolls are rotated, they alternately engage the supplying roll and then the passing ink rolls 11 between the disks 13. At the ends of the axle 57 are mounted gear wheels 60 driven from the gears 14 upon the shaft 3, a pair of pinions 61 being shown interposed between said gear wheels 60 and 14, although it is within the scope of the invention to interpose only one pinion if so desired, or in fact any number. Preferably there are a pair of ductor rolls upon diametrically opposite sides of the axle so as to balance the same and obtain a steady rotary movement, and since there are two sets of inking rolls rotating about the bed, I have shown the ductor axle geared to revolve once for each revolution of the ink roll supporting disks, but I do not restrict myself to this proportion of speeds inasmuch as the number of sets of ductor rolls may be varied, and more or less inking rolls may be used as desired.

Fresh ink is supplied to the exposed portion of the supply roll by revolving the same, and to this end a ratchet wheel 63 is fixed on the supply roll shaft, and a pawl 64 upon a lever 65 pivoted as at 66 is adapted to rotate the roll slowly by a step by step movement. This lever is preferably adjustable in length for varying the stroke of the pawl and is pivotally attached at its end to an eccentric 67 upon the ductor axle 57. Obviously the inked surface of the supply roll will be presented fresh to each engagement of the ductor rolls therewith so that fresh ink is supplied to the inking rolls. As the ink is thus supplied very shortly after the inking rolls have left the form, the ink becomes well worked before the same is applied to the form. In this

manner a very even distribution of ink is effected whereby a sharp and clear imprint may be obtained as the paper on the cylinder is passed thereover.

5 Suitable means are provided for gripping the paper at the proper time to hold it upon the cylinder while passing over the form to receive an imprint therefrom. One such means shown in Fig. 7 more especially comprises a plate 68 pivoted longitudinally in a recess 69 in the cylinder and adapted to grip the paper between itself and the cylinder. This plate is secured to a longitudinal rod 70 which projects at the ends of the cylinder 10 through the supporting rollers 46 and is resiliently rotated as by a spring 71 so as to normally press the plate against the cylinder and grip the paper. This spring is shown as fixed at one end to a drum 72 upon the rod 70 and secured at its other end to the roller 46. However, the resilient pressure may be effected in other ways than by this particular arrangement. For swinging the plate away from the cylinder to allow a sheet of 15 paper to be introduced therebetween or released therefrom at the proper time, a trip lever 72 is pivoted to the roller 46 and connected at one end by a flexible member such as a chain 74 to the periphery of the drum 70 so that swinging the lever rotates the drum. The other end of the lever lies adjacent the track upon which the roller 46 is riding and may be swung by engagement with any suitable protuberance 75 on said track. Such 20 protuberances are preferably placed one to open the gripping device to receive the paper previous to passing over the form and one to open the gripping device to allow the paper to discharge after passing over the form, the device remaining closed 25 or in its gripping position the remainder of its passage around the form-supporting member.

Any other suitable paper gripping means 30 may be employed, however, and obviously various other details of my invention may be changed or modified without departing from the spirit and scope of the invention, which is to apply the principle of a rotary 35 press to a flat-form press. I therefore do not wish to be understood as limiting myself by any of the positive description herein employed for purposes of illustration, except as required by the following claims when 40 construed in the light of the prior art.

It will be understood that the term "paper carrying cylinder" is used herein to designate any member whatever capable of being used for supporting or carrying the paper 45 while it receives an impression from the form or chase mounted upon the form-supporting means, whether in the shape of a cylinder or otherwise. The term is not to be limited to the particular means which I 50 have shown and described for purposes of

illustration but is to be understood as covering any means known to the art.

Having thus described the invention, what I claim is.

1. In a printing press, a stationary form 70 supporting member having a form supporting portion, tracks at opposite sides of said member, racks at opposite sides of said member, said tracks being between the racks and said member and both said racks and tracks 75 conforming in configuration to the contour of said member, compression rails at opposite sides of the form supporting member located in planes beyond the edges of said member and farther therefrom than the racks and spaced an even distance above the form supporting portion of said member for the entire length of said portion, a paper supporting cylinder, a pair of rollers on each end of the cylinder one of the rollers of each pair 80 riding upon said track and the other adapted to engage under the adjacent compression rail, and gears between the rollers of said pairs at opposite ends of the cylinder fast with respect thereto and in mesh with the racks for rotating the cylinder as they are revolved around the form supporting member.

2. In a printing press, a stationary form 85 supporting member having a form supporting portion, tracks at opposite sides of said member, racks at opposite sides of said member, said tracks being between the racks and said member and both said racks and tracks conforming in configuration to the contour 100 of said member, compression rails at opposite sides of the form supporting member located in planes beyond the edges of said member and farther therefrom than the racks and spaced an even distance above the form supporting portion of said member for the entire length of said portion, a paper supporting cylinder, rollers at each end of 105 said cylinder fast with respect thereto, another roller at each end of the cylinder loose 110 with respect thereto, said loose rollers being positioned farther apart than said fast rollers, the fast rollers riding upon said tracks and the loose rollers being arranged and adapted to engage under the adjacent compression rails and hold the cylinder in engagement with the form while passing over the same, and gears between the fast and loose rollers at the opposite ends of cylinder 115 in mesh with the racks and fast with respect to the cylinder for rotating the same as they are revolved around the form supporting member.

3. In a printing press, a stationary form 120 supporting member having a form supporting portion, a paper supporting cylinder adapted to revolve around said member and having a radial movement with respect thereto, springs tending to hold the cylinder normally outward away from said form 125 130

supporting member, and compression rails at the form supporting portion of said member adapted to counteract the outward push of the springs and cause the cylinder to engage 5 the form.

4. In a printing press, a stationary form supporting member having a form supporting portion, a paper supporting cylinder adapted to revolve around said member and 10 having a radial movement with respect thereto, springs tending to hold the cylinder normally outward away from said form supporting member, rollers on said cylinder, and compression rails in the planes of said rollers 15 adapted to overlie said rollers as the cylinder crosses the form supporting portion and counteract the outward push of the spring and cause the cylinder to engage the form.

5. In a printing press, a stationary form 20 supporting member having a form supporting portion, a paper supporting cylinder adapted to revolve around said member and having a radial movement with respect thereto, springs tending to hold the cylinder normally outward away from said form supporting member, compression rails at the form supporting portion of said member adapted to counteract the outward push of the springs as the cylinder crosses the form supporting 25 portion and cause the cylinder to engage the form, and means for limiting outward movement of the cylinder from the form supporting member during the period when the same is not operated upon by the compression rail.

6. In a printing press, a stationary form supporting member having a form supporting portion, a paper supporting cylinder adapted to revolve around said member and 40 having a radial movement with respect thereto, a spring tending to hold the cylinder normally outward away from said form supporting member, rollers on said cylinder, compression rails in the planes of said rollers 45 adapted to overlie said rollers as the cylinder crosses the form supporting portion and counteract the outward push of the spring and cause the cylinder to engage the form, and means for limiting outward movement 50 of the cylinders from the form supporting member during the period when the same is not operated upon by the compression rail.

7. In a printing press, a pair of separated rotatable disks, a stationary form between 55 said disks, a cylinder carried at its opposite ends by said disks and movable radially thereof, springs tending to hold the cylinder normally radially outward with respect to said disks away from said form supporting member, compression rails between the disks and the form supporting member, and rollers on said cylinder adapted to engage under the compression rails and thereby cause the cylinder to pass across the form in 60 predetermined relation thereto.

8. In a printing press, a pair of separated rotatable disks each having a radial slot adjacent its periphery, a stationary form between said disks, slidable bearings mounted in said slots, a cylinder carried at its opposite ends in said bearings and adapted thereby to be rotated and to be moved radially toward and away from the form supporting member, springs tending to hold the cylinder normally radially outward with respect to said disks away from said form supporting member, compression rails between the disks and the form supporting member, and rollers on said cylinder adapted to engage under the compression rails and thereby cause the cylinder to pass across the form in predetermined relation thereto. 70

9. In a printing press, a pair of separated rotatable disks each having a radial slot adjacent its periphery, a stationary form between said disks, slidable bearings mounted in said slots, a cylinder carried at its opposite ends in said bearings and adapted thereby to be rotated and to be moved radially toward and away from the form supporting member, springs mounted within said slots compressed between the inner ends of the slots and the bearings tending to hold the cylinder normally radially outward with respect to said disks away from said form supporting member, compression rails between the disks and the form supporting member, and rollers on said cylinder adapted to engage under the compression rails and thereby cause the cylinder to pass across the form in predetermined relation thereto. 80

10. In a printing press, a pair of separated rotatable disks each having a radial slot extending to its periphery, a stationary form between said disks, slidable bearings mounted in said slots, a cylinder carried at its opposite ends in said bearings and adapted thereby to be rotated and to be moved radially toward and away from the form supporting member, springs tending to hold the cylinder normally radially outward with respect to said disks away from said form supporting member, means limiting outward movement of the cylinder, and compression rails adapted to engage the cylinder when at its outward position and move it radially inward to pass the same across the form supporting portion of the member in engagement with the form. 105

11. In a printing press, a stationary form supporting member having a form supporting portion, a paper carrying cylinder tending normally to move away from the form supporting member and adapted to revolve around said member, a movable compression rail for guiding the cylinder across the form either in or out of contact therewith as desired, and means for rigidly supporting the compression rail in either position. 110

12. In a printing press, a stationary form 115

supporting member having a form supporting portion, a paper carrying cylinder tending normally to move away from the form supporting member and adapted to revolve around said member, a movable compression rail for guiding the cylinder across the form either in or out of contact therewith as desired, and an eccentric for rigidly supporting the compression rail either toward the 10 form supporting portion or away from the same as desired.

13. In a printing press, a stationary form supporting member having a form supporting portion, a paper carrying cylinder tending normally to move away from the form supporting member and adapted to revolve around said member, movable compression rails for guiding the cylinder across the form either in or out of contact therewith as 15 desired, and eccentrics at opposite ends of the compression rails for rigidly supporting the same either toward the form supporting portion or away from the same as desired.

14. In a printing press, a stationary form supporting member having a form supporting portion, a paper carrying cylinder tending normally to move away from the form supporting member and adapted to revolve around said member, movable compression rails for guiding the cylinder across the form either in or out of contact therewith as 25 desired, eccentrics at opposite ends of the compression rails for rigidly supporting the same either toward the form supporting portion or away from the same as desired, and means for turning said eccentrics simultaneously.

15. In a printing press, a stationary form supporting member having a form supporting portion, a paper carrying cylinder tending normally to move away from the form supporting member and adapted to revolve around said member, movable compression rails for guiding the cylinder across the 30 form either in or out of contact therewith as desired, eccentrics at opposite ends of the compression rails for rigidly supporting the same either toward the form supporting portion or away from the same as desired, and means for turning said eccentrics simultaneously.

16. In a printing press, a form supporting member, racks at opposite ends of said form supporting member, a paper carrying cylinder extending across said form and adapted to revolve around the same, gear wheels fast with respect to said cylinder in mesh with said racks adapted to rotate the cylinder as 55 the cylinder is revolved about the form supporting member, an ink roll adapted to re-

65
volve around said member, and gear wheels on said ink roll in mesh with the racks adapted to rotate the ink roll as the same is revolved about the form supporting member.

17. In a printing press, a frame, a stationary form supporting member thereon, a paper carrying cylinder adapted to revolve around said form supporting member, said cylinder having a roller at each end of itself fixed with respect to itself, a gripping plate pivoted to said rollers and overlying the cylinder, a drum fast with respect to said plate, resilient means tending normally to swing 70 said plate in one direction, a trip lever, and flexible means connecting the trip lever and drum for swinging the plate out of normal position against the action of said resilient means.

18. In a printing press, a frame, a stationary form supporting member thereon, a paper carrying cylinder adapted to revolve around said form supporting member, said cylinder having a roller at each end of itself 75 fixed with respect to itself, a gripping plate pivoted to said rollers and overlying the cylinder, a drum fast with respect to said plate, a trip lever, a spring adapted to wind around said drum in one direction, and flexible 80 means connected to the trip lever and adapted to wind around the drum in the opposite direction from the spring whereby rotation of the drum under action of the spring will wind the flexible member and 85 rotation of the drum under action of the flexible member will wind the spring.

19. In a printing press, a frame, a stationary form supporting member thereon, a paper carrying cylinder adapted to revolve 100 around said form supporting member, said cylinder having a roller at each end of itself fixed with respect to itself, a track for each of said rollers, means for revolving said cylinder around the form supporting member, a gripping plate pivoted to said rollers and overlying the cylinder, a drum fast with 105 respect to said plate at one end of the cylinder, a trip lever pivoted to one roller at the same end with said drum, a protuberance 110 on the track adapted to engage and swing the trip lever at a predetermined position of the cylinder, resilient means tending normally to swing said plate in one direction, and flexible means connecting the trip lever 115 and drum for swinging the plate out of normal position against the action of said spring in the other direction.

JAMES W. McNEIL.
